UNITED STATES PATENT OFFICE.

HEINRICH SCHOLL, OF PFORZHEIM, GERMANY.

FOLDABLE COMB.

Application filed June 21, 1926, Serial No. 117,553, and in Germany November 21, 1925.

Foldable combs have become known the elements of which are connected by hinges, said elements, if the comb is unfolded, being stiffened in this position, by means of a slide pushed over the back of the comb at the joint. These combs present the inconveniences, that the hairs are caught in the hinges which are open on the surface of the comb, that the hinges are foldable only in one direction and are easily broken out of the comb if accidentally the comb is folded in the wrong direction, and that further the slides are too short and too narrow and consequently do not sufficiently stiffen the comb. The hinges on the outer side of the comb do not improve the appearance of the comb.

The foldable comb according to this invention is free from the inconveniences mentioned, and, in the position of use, it is stiffened by a slide in such a manner that it is even more resistant than an ordinary comb.

According to the invention the comb has a double hinge at the joint between its two elements which double hinge is sunk into the comb back. The slide is long and ornamented and it is guided in longitudinal direction by means of a guide rib in a groove cut into the surface of the comb back. The sunk double-hinge permits of folding the comb to either side, any breaking of the elements at the joint being avoided. The slide can be pushed over the joint so that it covers the same and it is impossible that hair be caught in the hinge if the comb is used.

An embodiment of the invention is shown, by way of example, in the accompanying drawing in which:—

Fig. 1 shows the unfolded comb in the 40 position of use in elevation.

Fig. 2 is a top plan view of Fig. 1.

Fig. 3 shows in elevation the comb folded.

Fig. 4 is a plan view of Fig. 3.

Fig. 5 is a cross section of the comb in 45 the position of use.

Fig. 6 shows in end elevation the joint between the two elements of the folded comb.

The elements *a*, *b* of the comb are connected with one another by a double hinge *c* sunk into the comb back so that the comb can be folded in both directions. A slide *d* of U-shaped vertical section is slidably mounted on the comb back and guided by 55 means of a guide rib *e* in a groove *f* cut into one surface of the comb back. The slide *d* serves to stiffen the comb in the position of use and it covers the sunk double hinge *c*.

I claim:—

A folding comb comprising in combination with the two halves, a double hinge connecting with one another said two comb-halves and sunk into the comb back which has 65 a longitudinal groove in one of its surfaces, a slide of U-shaped section shiftably mounted on said comb back, and a rib on the inner surface of said slide and engaging with said groove in the comb back.

In testimony whereof I affix my signature.

HEINRICH SCHOLL.
